UNITED STATES PATENT OFFICE.

PAUL H. HORWITT, OF BROOKLYN, NEW YORK, ASSIGNOR, BY MESNE ASSIGNMENTS, TO INDEPENDENT PAPER MILLS, INC., OF BROOKLYN, NEW YORK, A CORPORATION OF NEW YORK.

HOLDER FOR SHEETS ARRANGED IN PILES.

Application filed June 27, 1922. Serial No. 571,296.

To all whom it may concern:

Be it known that I, PAUL H. HORWITT, a citizen of the United States of America, and a resident of the borough of Brooklyn, county of Kings, city and State of New York, have invented certain new and useful Improvements in Holders for Sheets Arranged in Piles, of which the following is a specification.

10 My invention relates to holders for sheets arranged in piles, and more particularly to holders for paper napkins, paper towels, toilet paper and the like, and has for its object to provide a novel and improved arrangement whereby a pile of such napkins, towels, toilet paper or the like is supported in a manner to facilitate the removal of individual napkins, towels, sheets of toilet paper and the like from the top of the pile.

15 Another object of the invention is to provide means whereby withdrawal of napkins, towels, sheets of paper and the like from the pile at intermediate points thereof is prevented. Other more specific objects will 20 appear from the description hereinafter and the features of novelty will be pointed out in the appended claims.

In the accompanying drawings, which illustrate an example of the invention without defining its limits, Figure 1 is an elevation of the holder; Fig. 2 is a plan view; Fig. 3 is a sectional view on the line 3—3 of Fig. 2, and Fig. 4 is a detail view illustrating another form of the invention.

35 In its essentials, the invention comprises a device which, by its weight, depresses the napkins, towels, toilet paper or other folded sheets at the upper end of a pile in a manner to bulge the central portions of the terminal napkins or the like, whereby the removal of individual napkins or other folded sheets is facilitated. In the preferred arrangement the paper napkins or other sheets, folded into rectangular, oblong form, are 40 piled so that alternate napkins or other sheets cross and project beyond each other, with the result that at its centre the pile is composed of a plurality of thicknesses of sheets in excess of the thickness of the pro-

jecting portions of the pile, and the device 50 is constructed so as to exert a pressure only upon said projecting portions; in this way, the central portions of the uppermost folded sheets are bulged upwardly and the folded edges are accentuated so as to be capable of 55 being lifted by the fingers when a napkin or other sheet is desired.

In the illustrated example, the invention consists of a stand 10, upon which a support 11 in the form of a plate is mounted, upright guide members or posts 12 projecting upwardly from said support in a manner to define guideways or spaces for the projecting ends *a* of the pile of paper napkins or other sheets *b*. The latter, as shown, may 60 be folded into oblong, rectangular form and in any case, are arranged cross-wise or transversely of each other, so that the central portions *c* of the pile are located centrally between the posts 12. Because of the fact 65 that the central portions of the napkins or other folded sheets are all superimposed directly upon each other while the projecting ends of alternate napkins or other folded sheets extend transversely to each other, the 70 central portion *c* of the pile is relatively 75 thicker than the projecting ends *a* thereof. Thus, if the latter are depressed from above, the central portions *c* will be bulged upwardly, with the result that the edges *d* 80 of the uppermost napkins or other folded sheets of the pile are separated and easily 85 picked up by the fingers, so that individual napkins or other sheets *b* may readily be lifted from the pile. The device whereby 90 the depression of the sheets is accomplished may, as shown, comprise a member 13 having a central aperture 14 and notches 15 arranged to fit over the posts 12; if desired, the latter may be provided with projections 95 16 in the form of spherical ends or balls to prevent unintentional removal of the member 13, intentional removal of said member being readily accomplished by exerting a 100 lifting force upon said member 13 sufficient to spring one or more of said posts inwardly to a slight extent. The member 13, when in operative position, rests upon the pile of 105

napkins or other folded sheets, and by its weight, bears against the projecting ends *a* and depresses the same, whereby the central portions *c* of the uppermost folded sheets 5 are bulged upwardly through the aperture 14, as shown in Figs. 1 and 3.

Any suitable means may be included in the holder for preventing removal of napkins *b* or other folded sheets from intermediate 10 points of the pile; for instance, flanges 17 may be provided and arranged so as to project over the upright surfaces of the pile to an extent sufficient to accomplish the desired purpose. In the illustrated example 15 shown in Figs. 1, 2 and 3, these flanges 17 are carried by and depend from the member 13 over the edges of the projecting ends *a*, as indicated in Figs. 1 and 3. With this arrangement, which is intended to exemplify 20 equivalent constructions, the end edges of a sufficient number of the uppermost napkins or other folded sheets are rendered inaccessible, so that it is impossible to withdraw napkins or the like from any intermediate 25 points of said pile, it being apparent that the difficulty of extracting folded sheets from points below said flanges 17 in the illustrated example, will discourage any attempt at withdrawal from the lower portions of the 30 pile. An equivalent structure is shown in Fig. 4, in which the flanges 17 project upwardly from the plate 11 over the end edges of the pile of napkins.

The invention provides a holder of simple and inexpensive construction, whereby 35 the napkins or other sheets, and more particularly paper napkins, are displayed in a sanitary and attractive manner; the upward bulging of the uppermost sheets in the pile 40 so accentuates the longitudinal edges thereof at the central portion *c* as to indicate immediately how individual napkins or other sheets may be removed without effort. This is accomplished by exerting a lift upon the 45 terminal napkin or its equivalent sufficient to separate it from the pile and draw it through the aperture 14, as indicated by dotted lines in Fig. 1, the adjacent napkins or other sheets being held against disturbance by the weight 50 of the member 13. The pile of sheets is easily placed in position upon the support 11 between the posts 12 which not only fix the pile in place, but serve also as guides for the member 13, which gradually descends as 55 the napkins or their equivalents are successively removed. The invention eliminates waste and yet makes it easy to procure as many napkins or other sheets as may be desired, and at the same time does away 60 with indiscriminate handling, for instance, of napkins or towels and the like, so that the latter are protected against contamination and are maintained in a sanitary, wholesome condition.

65 If desired, instructions in the use of the

holder may be produced, for instance, upon the flanges 17 or upon any other convenient part thereof.

Various modifications may be made within the scope of the claims without departing 70 from the nature of my invention.

I claim:

1. The combination of a support, a pile of sheets carried thereby and having a central area of greater density than adjacent 75 outer areas thereof, means for maintaining said pile in place upon said support, and a device adapted to depress said pile at its areas of lesser density, whereby the sheets at the top of said pile are bulged outwardly 80 at the central area of greater density to facilitate removal of individual sheets.

2. The combination of a stand, upright 85 guide members on said stand, a pile of paper napkins supported on said stand between said guide members and having alternate napkins arranged in transverse relation to each other to produce a central area of greater density than adjacent outer areas located between and beyond said guide 90 members, and a device arranged to depress said pile at its areas of lesser density outside of the guide members whereby the napkins at the top of said pile are bulged outwardly at the central area of greater density 95 inside of said members to facilitate removal of individual napkins.

3. The combination of a stand, a pile of napkins thereon, in which alternate napkins cross and project beyond each other to 100 produce outer areas of lesser density than that of the central area of said pile, upright posts on said stand between which said pile is positioned, and an apertured member arranged to exert a pressure upon 105 said outer areas of said pile whereby the napkins at the top thereof are bulged upwardly at the central area of greater density through the aperture of said member to facilitate the removal of individual napkins therethrough. 110

4. The combination of a stand, a pile of napkins thereon, in which alternate napkins cross and project beyond each other to produce outer areas of lesser density than that 115 of the central area of said pile, upright posts on said stand between which said pile is positioned, an apertured member arranged to exert a pressure upon said outer areas of said pile whereby the napkins at the top thereof are bulged upwardly at the central area of greater density through the aperture of said member to facilitate the removal of individual napkins therethrough, and means whereby withdrawal of napkins 120 from said pile at intermediate points is prevented. 125

5. The combination of a stand, a pile of napkins thereon in which alternate napkins cross and project beyond each other to pro- 130

duce outer areas of less density than the central area of said pile, upright posts on said stand between which said pile is positioned, an apertured member arranged to exert a pressure upon said outer areas of said pile whereby the napkins at the top thereof are bulged upwardly at the central area of greater density through the aper-

ture of said member to facilitate the removal of individual napkins therethrough, and flanges depending from said member to prevent withdrawal of napkins from said pile at intermediate points.

In testimony whereof I have hereunto set my hand.

PAUL H. HORWITT.
